William E. Rieark

UNITED STATES PATENT OFFICE.

SWAN A. NELSON, OF TUNNEL HILL, PENNSYLVANIA.

ANCHOR AND BRACE FOR RAILS OF RAILWAY-TRACKS.

1,321,121.

Specification of Letters Patent.

Patented Nov. 11, 1919.

Application filed March 6, 1919. Serial No. 281,021.

To all whom it may concern:

Be it known that I, SWAN A. NELSON, a citizen of the United States, residing at Tunnel Hill, Cambria county, State of Pennsylvania, have invented a new and useful Improvement in Anchors and Braces for Rails of Railway-Tracks, of which the following is a specification.

This invention relates to anchors and braces for the rails of railroad tracks, and has for its object to form a device of this nature that shall be simple and cheap to manufacture, easy of application, and efficient in use; to provide a device that will prevent the rails of a railroad track from spreading, thereby preventing accidents; to make such a device adjustable so as to accommodate different gages of tracks; to provide means for securing said device to the ties of the track so that it will be securely fixed thereto; and finally, to provide an efficient brace for the rail that will brace the rail against side strains, and add in holding it in place.

These and other objects of my invention are set forth in the following specification, and shown in the drawings annexed hereto, which form a material part of this disclosure, and in which:—

Figure 1 is a transverse sectional view of a track showing my rail anchor and brace. Fig. 2 is a plan view thereof.

Fig. 3 is a detail sectional view taken on line 3--3 of Fig. 1.

Fig. 4 is a detail face view.

Fig. 5 is a detail sectional view showing the insulating connection between the two halves of the tie rod.

Referring to the drawings, 1 represents the rails and 2 the ties of a railroad track, the rails being secured upon the ties in the usual manner.

In order to prevent the spreading of the rails, I form a tie rod comprising the anchor members 3 in the form of flat strips, the outer ends of which are bent over upon themselves as at 4, to form hooks which are adapted, when the anchor members are passed under the tie, to pass around and clamp tightly upon the outer side of the base flange 1 of the rail. The inner ends of the anchor members terminate in rods 3' united to one another by a connection which maintains them electrically insulated from each other.

As here shown these inner ends have round nuts 5 screwed thereon and held by set screws 5'. Inclosing these heads are insulating sleeves 6 upon which are mounted the caps 7 having their exteriors formed with right and left screw threads respectively. A coupling 8 having correspondingly threaded opposite ends, is secured on the caps 7.

These anchor members each have two openings formed therein adjacent the base flange 1'. One of these openings is adapted to receive the screw-threaded stem 10 of a clamp 11 which, as shown in Fig. 3, is so formed as to pass around the bottom and part of the sides of a tie and engage the same closely. Nuts 12 and 13 engage the screw-threaded stem 10 on the opposite sides of the anchor member to hold the said stem in place with relation to the latter. A brace 15 is adapted to sit on the flange 1' and closely fit the web 1 of the rail on the inner side thereof and has a downwardly projecting screw-threaded stem 16 passing through the other opening in the anchor 3, and held in place therein by the nuts 17 and 18 on the opposite side of the anchor.

A supporting member 20 is fitted against the rail on the opposite side to the brace and fits snugly between the tread 16 of the rail and the base flange 1' thereof.

This member 20 is secured in place by a bolt 21 passing through an opening 22 therein, and through a suitable opening in the web of the rail and also through a vertical slot 23 in the brace whereby the brace and supporting member are both secured to the rail. Formed integral with the supporting member are downwardly projecting lugs 25 which are adapted to straddle the tie.

In operation, the rails being set to gage, my anchor members are secured in position upon the rails, the clamping ends closely engaging the outer side of the base flanges when the turn-buckle 1 is turned to bring the screw-threaded stems of the anchor members into position to bring and hold said members and rails in the desired position with relation to each other. The clamp is placed around the tie and its end is secured to the anchor member, the brace and supporting member are also put into position, as above described, with the result that the rails will be held firmly in position by said

anchor members and braces and by said clamp, and will be prevented from spreading and be braced against side strains.

Having thus described my invention and 5 set forth the manner of its construction, what I claim as new, and desire to secure by Letters Patent is:—

1. A device for preventing the spreading of the rails of railroad tracks, comprising a 10 pair of anchor members engaging the respective rails at opposite ends and connected to one another, rigid straps connected at one end to said anchor members and extending under and engaging one of the ties, braces secured 15 to the anchor members and resting against the webs and base flanges of the rails on the inner sides thereof, and supporting members resting against the webs and base flanges of the rails on the outer sides thereof, and bolts 20 passing through the rails, supporting member and braces and securing said supporting member and braces in position.
2. A device for preventing the spreading of the rails of railroad tracks, comprising a 25 pair of anchor members engaging the respective rails at opposite ends and straps connected at one end to said anchor members and extending under and engaging one of the ties, braces secured to the anchor members 30 and resting against the webs and base flanges of the rails on the inner sides thereof, and supporting members resting against the webs and base flanges of the rails on the outer sides thereof, and bolts passing 35 through the rails, supporting members and braces and securing said supporting mem-

bers and braces in position, the said braces having vertical slots formed in the upper ends thereof to receive the said bolts.

3. A device for preventing the spreading 40 of the rails of railroad tracks, comprising a pair of anchor members engaging the respective rails at opposite ends and connected to one another, rigid straps connected at one end to said anchor members and extending under and engaging one of the ties, braces secured to the anchor member and resting against the webs and base flanges of the rails on the inner sides thereof, and supporting members resting against the webs 45 and base flanges of the rails on the outer sides thereof, and bolts passing through the rails, supporting member and braces and securing said supporting member and braces in position, the said braces having vertical 50 slots formed in the upper ends thereof to receive the said bolts and the said supporting members having lugs formed thereon adapted to straddle the railroad tie engaged by the said strap.

4. The combination with a pair of anchor members forming a tie rod for rails, of heads formed on the adjacent ends of said members, insulating sleeves upon said members surrounding said heads, caps surrounding said insulating sleeves, said caps being exteriorly screw threaded, and a coupling member screwed upon said caps.

In testimony whereof I have signed my name to this specification, this 4th day of 70 March, 1919.

SWAN A. NELSON.
